UNITED STATES PATENT OFFICE.

ADOLPH ROSEDALE, OF TALLAHASSEE, FLORIDA, ASSIGNOR TO THE ROSEDALE AUTOMATIC DISH-WASHING MACHINE COMPANY, OF ILLINOIS.

DISH-CLEANSING APPARATUS.

SPECIFICATION forming part of Letters Patent No. 660,314, dated October 23, 1900.

Application filed December 18, 1899. Serial No. 740,788. (No model.)

To all whom it may concern:

Be it known that I, ADOLPH ROSEDALE, a citizen of the United States, residing at Tallahassee, in the county of Leon and State of Florida, have invented a new and useful Improvement in Dish-Cleansing Apparatus, of which the following is a specification.

My invention relates particularly to an improvement in machines for cleansing dishes, though the device may be used for cleansing many other articles.

My object is to provide for the purpose stated a machine of large capacity, of cleanly and easy operation, and free from all objectionable moving parts and mechanisms.

In perfecting this invention important features of consideration have been those of cheapness of production and operation, avoidance of danger of chipping or breaking dishes, and the presence of perfect hygienic conditions.

In the preferred construction shown in the accompanying drawings a cabinet is provided containing a stationary steam stand-pipe and a stationary hot-water stand-pipe, said stand-pipes being connected in several planes by relatively small sinuous perforated spraying-pipes, which thus as open-work shelves divide the cabinet into a number of superimposed compartments for receiving dish-trays. Preferably the water stand-pipe connects with a boiler below the water-level, and the steam stand-pipe connects with the steam-dome of said boiler. Under the most usual and satisfactory conditions no moving parts other than the valves and cabinet-door are required.

In the drawings, Figure 1 is a broken view, in front elevation, of the cabinet, the boiler, and the connections and fittings; Fig. 2, a broken plan view thereof; Fig. 3, a vertical section parallel to the front of the cabinet, as indicated at line 3 of Figs. 2, 4, and 5; Fig. 4, a vertical section at line 4 of Fig. 3; Fig. 5, a plan section at line 5 of Fig. 3; Fig. 6, an enlarged broken perspective view of a portion of the perforated pipe-shelving, and Figs. 7 and 8, details of one form of door-fastening means which may be employed.

50 A represents a boiler or other source of

steam and hot-water supply; B, a cabinet supplied with a vertical hot-water stand-pipe B', a similar steam stand-pipe B² and horizontally-disposed perforated shelf-forming spraying-pipes B³, connecting said stand-pipes in several horizontal planes, thereby dividing the cabinet into superimposed tray-receiving cleansing-compartments a, a', &c.; C C', supports for said tubular shelves, comprising upright rods b and perforated cross-bars b', receiving said rods and rigid therewith; D, a steam-supply pipe leading from the steam-dome of the boiler to the upper end of the stand-pipe B² and provided in its course with a valve D'; E, a water-supply pipe leading from the boiler below its water-line and connecting with the upper end of the stand-pipe B', being supplied in its course with a valve E'; F, a vapor exhaust or education pipe leading from the top of the cabinet and supplied with a valve F'; G, a waste-water education-pipe leading from the bottom of the cabinet and provided with a valve G'; H, a pressure-gage communicating with the interior of the cabinet, and I a door for the cabinet, which in the construction shown is mounted on hinges I' and secured by fastenings I².

As appears from Figs. 5 and 6, each shelf-forming steam and water pipe B³ comprises, 80 preferably, parallel transversely-extending sections d, joined in alternation at their ends by short sections d' and elbow-couplings d² to afford a continuous sinuous channel extending from one stand-pipe to the other. I 85 have shown each transverse pipe and each short section provided with four rows of perforations; but obviously the number and position of the perforations may be changed at will.

The transverse pipes are of less diameter than the stand-pipes, and those belonging to a given shelf-forming series are spaced at a few inches apart, the perforations being minute and at close intervals. The lower portions of the stand-pipes are connected by the lowermost shelving-tube B³, and thus terminate in blind ends, except for the perforations in the shelf-tubing.

Figs. 7 and 8 show, respectively, a portion 100

of the front plate of the casing to the right of the door in Fig. 1 and a portion of the right-hand portion of the door when secured to said plate. The periphery of the door-opening is 5 provided with a raised plate *e*, supplied with a gasket or packing-strip *e'*, against which the periphery of the inner surface of the door bears in the closed position. The door is provided at its edges with slotted lugs *f*, which 10 receive the outer ends of headed bolts *f'*, secured at their inner ends by pins *f''* to lugs *f'''* on the plate *e*. The bolts *f'* are supplied with loose cam-collars *f⁴*, having handles *f⁵*. In Fig. 8 one of the bolts is shown engaging 15 a slotted lug, while the dotted and full positions of the cam indicate, respectively, the position before and after tightening. The hinges *I* are of a construction and location to cause the rear edge of the door to clear the 20 fastenings thereat in swinging. In practice the door may be of any suitable construction to secure quickness of operation and reasonable tightness of joint.

In operation the cabinet may be prepara- 25 torily heated by closing all eduction-valves and opening only the steam-admission valve for a short time. The dishes may be introduced into the cabinet conveniently by means of open-work trays, which permit impinge- 30 ment of the jets from all directions. Fig. 5 shows, by means of dotted lines, a convenient form and location for these trays. It will be observed that the size of the door-opening is materially reduced by locating the door cen- 35 trally and shoving the first trays of a given tier inserted to the sides of the cabinet, the central tray being last inserted. In remov- 40 ing the trays the center tray is removed first. After the trays are in place and the door se- 45 cured the eduction-valves are opened wide and the steam - admission valve is opened slightly, and afterward the water-admission valve is opened. Both admission-valves are then opened to the extent desired, and after 50 a very short interval the dishes are ready for removal. Before the door is opened the admission-valves are closed to prevent any water from being thrown out of the cabinet. The eduction-ports are large enough to allow 55 the vapor and waste water to pass without hindrance from the cabinet, and the interior of the cabinet is left perfectly clean. After the first washing the cabinet is quite warm and tends to dry the dishes rapidly when the 60 water and the steam supply are shut off. The heat of the dishes finishes the drying opera- 65 tion after removal, and it is found that the dishes are thoroughly cleansed and highly polished.

60 It is noteworthy that no soap or other sim- 65ilar disagreeable or unhygienic agent is re- required even for dishes which are very greasy and otherwise soiled. No partially-decayed food particles remain, and the dishes come 65 from the cabinet after subjection to a germi- cidal heat. Since no pressure is maintained in the cabinet during the washing operation,

the walls thereof may, if desired, be of light sheet metal inclosed in a non-conducting cas- 70 ing.

I attribute the splendid cleansing and pol- 75 ishing effect attained with the device largely to the fact that the hot water and steam are conducted to the cabinet through separate channels and there intimately mingled, where- 80 by both a higher degree of heat results in the cabinet and also the hot-water jets are caused to issue with greater velocity owing to the conversion of heat energy into mechanical en- 85 ergy through the condensation of the steam. 80 Nevertheless the invention is not limited to the use of both steam and hot water, as the con- 90 struction has many advantages even though certain features are omitted. The disposition and construction of the spraying pipes or 95 heads are such that the spray is directed against the dishes from all sides, the effect being to prevent movement of the dishes even though streams of great force are used. By 100 employing a stand-pipe and the several spray- 90 pipes connected therewith and lying in several planes the capacity of the apparatus is increased greatly. Thus it is perfectly practicable to construct a cabinet having a capacity of from eight hundred to one thou- 105 sand pieces within easy range of an attend- 100 ant and provided with a single door. The sinuous form of each spraying-pipe may be departed from; but it is important that in each of the dividing-planes, or planes sepa- 110 rating the compartments, a spraying-head shall be provided having such number and disposition of perforations as to cause practi- 115 cally a sheet of water-jets to be ejected upon the dishes.

105 In the apparatus shown the pressure which 110 delivers the water to the spraying-heads is the steam-pressure of the boiler.

What I claim as new, and desire to secure by Letters Patent, is—

110 1. In apparatus of the character described, 115 the combination with a hot - water - supply source, of a plurality of spraying-heads lying in different horizontal planes and forming a plurality of superimposed spraying-compart- 115 ments, substantially as and for the purpose set forth.

2. In apparatus of the character described, 120 the combination with a hot - water - supply source, of a plurality of spraying-heads lying in different planes and forming a tray-receiving compartment, said heads being provided on adjacent sides with a large number of perforations disposed close to each other throughout the planes of said heads, and serving to 125 simultaneously project sheets of water-jets, substantially as and for the purpose set forth.

3. In apparatus of the character described, 130 the combination with a hot - water - supply source, and a supply-pipe leading from said source, of a plurality of spraying-heads lying in different horizontal planes and forming a series of spraying-compartments, each of said spraying-heads comprising a plurality of pipe-

sections connected with each other, said pipe-sections being disposed in close relation to each other and provided with perforations, substantially as and for the purpose set forth.

5 4. In apparatus of the character described, the combination with a hot - water - supply source, a supply-pipe leading therefrom, a cabinet, a stand-pipe therein connected with said supply-pipe, and a plurality of spraying-heads connected with said stand-pipe and forming tray-receiving compartments, each of said spraying-heads comprising a series of perforated pipe-sections connected together, substantially as and for the purpose set forth.

15 5. The combination with a hot-water-supply source and a steam-supply source, of a plurality of spraying-heads located in different planes to afford a tray-receiving compartment, a steam-pipe connecting the source of steam-supply with said spraying-heads, and a hot-water pipe connecting the source of hot-water supply with said spraying-heads, substantially as and for the purpose set forth.

25 6. The combination with a steam-supply source and a hot-water-supply source, of a cabinet, a steam stand-pipe in said cabinet, a hot-water stand-pipe in said cabinet, and a plurality of spraying-heads connected with both said stand-pipes and dividing the cabinet into tray-receiving compartments, substantially as and for the purpose set forth.

35 7. The combination with a steam-supply source and a hot-water-supply source, of a cabinet, a steam stand-pipe in said cabinet and a hot-water stand-pipe in said cabinet, and a plurality of spraying-heads connected with both said stand-pipes and dividing the cabinet into tray - receiving compartments, each spraying - head comprising perforated pipe-sections connected together, substantially as and for the purpose set forth.

40 8. The combination with a steam-supply source and a hot-water-supply source, of a cabinet, a steam stand-pipe in said cabinet, and a hot-water stand-pipe in said cabinet, a plurality of spraying-heads connected with both said stand-pipes and dividing the cabi-

net into tray-receiving compartments, each spraying-head comprising a sinuous perforated pipe of less diameter than the stand-pipes, substantially as and for the purpose set forth. 50

9. The combination of a boiler, a steam-supply pipe connected with the steam-dome of said boiler, a hot-water-supply pipe connected with said boiler below the water-level thereof, and a plurality of spraying-heads located in different planes and connected with said supply-pipes, substantially as and for the purpose set forth. 55

10. The combination with a boiler, of a hot-water-supply pipe connected therewith below the water-level thereof, a cabinet, and a plurality of spraying-heads within said cabinet, said spraying-heads being supplied with water under steam-pressure from the boiler, substantially as and for the purpose set forth. 65

11. The combination of a steam - supply source, a hot-water-supply source, a cabinet, steam and hot-water spraying-heads in said cabinet in communication with said steam and hot-water supply sources, valves controlling the flow of steam and water into said heads, an eduction-port for said cabinet, and a valve controlling the eduction-port. 70

12. The combination of a steam - supply source, a hot-water-supply source, a cabinet, steam and hot-water spraying-heads in said cabinet in communication with said steam and hot-water supply sources, valves controlling the flow of steam and water into said heads, and a valved water-eduction port and a valved vapor-eduction pipe for the cabinet. 80

13. The combination of a cabinet, stand-pipes B' B² therein, spraying-heads B³ comprising perforated sinuous pipes connecting said stand-pipes, and supports for said perforated pipes at the loop ends thereof, substantially as and for the purpose set forth. 85

ADOLPH ROSEDALE.
